ETCHING MACHINE

John A. Easley, William E. Eden, and Harry E. Swayze, Midland, Mich., assignors to The Dow Chemical Company, Midland, Mich., a corporation of Delaware

Application November 26, 1952, Serial No. 322,650

6 Claims. (Cl. 41—9)

1

The invention relates to etching machines, especially those adapted to etch metal plates, such as printing plates and the like. The invention more particularly concerns an improved etching machine of the type wherein the work to be etched is held over a tank of etching acid and the acid is splashed against the work by means of rotating paddles which dip into the acid.

In conventional etching machines of the type with which the invention is concerned, there is the difficulty that the plates are not always uniformly etched. This difficulty, we have found, is due to the fact that some portions of the plate undergoing etching persistently receive a more vigorous splashing of etching acid than others. It is one of the principal objects of the invention to overcome this difficulty by providing means for ensuring a uniform action of the acid on all portions of the work so that during the time the work is being etched each portion will on the average receive the same amount of splashing and the impinged acid will produce a uniform etch over all the exposed portions of the work. This object is attained according to the invention by providing means for giving the work a random motion while the etching acid is splashed against the work. Other objects and advantages of the invention will appear from the following description and accompanying drawing illustrating a preferred embodiment of the invention.

Fig. 1 is a plan view of the apparatus with the cover lowered into place over the etching acid tank, some parts of the cover being cut away to show internal structure.

Fig. 2 is a vertical cross section on the line 2—2 of Fig. 1.

Fig. 3 is a rear elevation of a portion of the apparatus with the cover lowered into place over the etching acid tank.

Fig. 4 is a fragmentary side elevation of the apparatus showing the cover in a raised position.

Fig. 5 is a plan view of the underside of the cover showing the holder for the work to be etched.

Fig. 6 is an enlarged view of a portion of the mechanism on the top side of the cover.

Referring to the drawing, there is shown an open top rectangular tank indicated generally by numeral 1 for holding the etching acid 2. The tank rests on a rectangular framework 3 supported by legs 4. The bottom 5 of the tank slopes toward an outlet 6 which is provided with a drain pipe 7 having a valve 8 which may be opened for

2

draining the tank. Depending from the inside of the rim 9 of the tank along one side and offset therefrom is an upstanding baffle 10, the lower edge of which is above the bottom 5 of the tank. Inside the tank just below the rim 9 along the front, rear, one side and baffle 10 is a ledge 11 in the form of pieces of angle iron secured to the said baffle and sides of the tank. The ledge stiffens the rim of the tank and baffle 10 and forms a support for the cover 12 which rests upon the ledge 11 when the cover is in the position in which it forms a closure for the tank as in Fig. 1.

As shown, the cover 12 is a rectangular metal plate which is just large enough to lie inside the rim 9 of the tank and upstanding baffle 10. The periphery of the cover is stiffened with angle members 13 secured to the underside parallel to and spaced from the outer edges so that the depending flange portion 14 lies inside the ledge 11 as shown when the cover is in place. The cover is arranged to be tipped upwardly at the front edge 15 to give access to the tank and work holder plate 16 referred to later.

The upward tipping of the front of the cover is facilitated by the arms 17 while the rear edge 18 is carried by the wheels 19 which are attached to the rear of the cover and ride on the ledge 11 as the front edge of the cover is raised, as by the handle 20. As shown, the arms are journalled on a cross bar 21 which is supported at each end by the columns 22 attached to the legs 4. One end of each of the arms is fixed to a counterweight 23 and the other end of each of the arms is pivoted in a bracket 24 which is secured to the upper side of the cover.

One side of the tank just below the ledge 11 is provided with an opening 25 communicating with a flue 26 for venting fumes from the tank. Inside the tank opposite the opening is a baffle 27 to prevent the escape of acid spray during operation.

Along the inside of and offset from the front 28 and rear 29 of the tank are baffles 30 and 31, respectively.

Arranged across the tank in a plane and spaced above the bottom is a series of paddle shafts 32 which pass through openings 33 and 34 in the front and rear sides of the tank, respectively, and openings 35 and 36 in the adjacent baffles, 30 and 31, respectively. The shafts are journalled in bearings 37 which are mounted on brackets 38 attached to the legs 4. Near each end of each shaft between the tank and the adjacent baffle is a spinner ring 39 which in combination with the adjacent baffle prevents escape

of acid spray through openings 33 and 34 in the tank during operation. Each shaft carries a paddle blade 40 formed in two parts 41 and 42 clamped on to and extending the length of the shaft between the baffles 30 and 31, the width of the paddle blade being sufficient to permit the outer edges to dip into the etching acid when the tank is appropriately filled with acid for etching. With this arrangement of paddles, the working depth of the acid in the tank will be below the openings 33 and 34 in the sides of the tank through which the paddle shafts pass but above the outer edges of the paddle blades when the latter are turned into the vertical plane. Between each of the adjacent paddle blades is a vertical baffle 43 which is mounted at either end on the front and rear baffles 30 and 31.

On one end of each paddle shaft is mounted a pulley 44, and, by means of three belts 45, 46, and 47 each engaging two of the paddle shaft pulleys, all of which are the same diameter, and a sheave of the multisheaved motor pulley 48, the paddles are driven at the same speed by motor 49.

Means for controlling the temperature of the etching acid are provided as by a heat exchanger in the form of the pipe coil 50 which is disposed on the inside of the bottom of the tank below the paddle blades. The pipe coil has an inlet 51 which is connected to a source of heat transfer fluid (not shown) at a desired temperature and an outlet 52 for the heat transfer fluid which traverses the pipe. The inlet and outlet are arranged to enter the tank between the side of the tank and the upstanding baffle 10 thereto adjacent. As a means to ensure homogeneity of the etching bath composition during operation (in addition to the agitation produced by the paddles) pipes 53 and 54, provided with small openings 55 along the sides, are arranged in the tank adjacent to the pipe coil. The pipes are connected together and to the delivery side of a circulation pump 56 by a pipe 57 while the suction side of the pump is connected to the drain 7 by a pipe 58. Pipes 53 and 54 enter the tank between the side of the tank and the upstanding baffle 10 thereto adjacent. The circulation pump 56 may be driven by motor 49 through the belt 59.

The work to be etched, e. g. a printing plate 60, is held on the underside of the cover on the work holder plate 16 by means of clamps 61 and 62. As shown, one of the clamps, for example 61, is secured to the work holder plate by means of bolts 63, the other is clamped in a slot 64 in the work holder plate by clamping screw 65 so that the distance between the two clamps is adjustable to permit clamping in place work pieces of various sizes. The work holder plate 16 is mounted for rotation in a plane parallel to the cover on the lower end of the shaft 66 which extends through a slotted opening 67 in the cover.

The other end of the shaft is journalled in bearings 68 which are mounted upon a carriage plate 69. The carriage plate is mounted on bearings 70 which are adapted to slide on ways 71 mounted on the top of the cover.

As shown, the shaft 66 carries a pinion 72, the teeth of which are adapted to engage the teeth 73 at either end of a rack 74, secured to the cover, as the carriage plate is reciprocated back and forth along the ways 71 from one end to the other. The toothed portion of one end of the rack is longer than the toothed portion at the opposite end and asymmetrically placed

with respect to the midpoint of the rack as shown particularly in Fig. 6. The reciprocatory movement is imparted to the carriage plate by the connecting rod 75 one end of which is pivoted to the bracket 76 on the carriage plate and the other pivoted to the crank 77 of the speed reducing gear box 78. The speed reducing gear box is driven by motor 79 through belt 80. With this arrangement, a rotational motion is given to the work holder plate 16 while the carriage plate is moved along the ways and the pinion engages the rack but not when the pinion is between the toothed portions of the rack, in the space 81, in which the pinion does not engage rack teeth but is free to coast.

In operation, sufficient etching acid is placed in the tank 1 to bring the upper surface 82 of the etching acid bath to about $\frac{1}{4}$ inch, for example, above the periphery of the path of revolution 83 of the paddle blades as shown in Fig. 2. Before starting the apparatus, the cover 12 is lifted upwardly at the front edge by means of handle 20 into the position shown in Fig. 4 so as to give access to the underside of the cover and the work holder plate 16. The work to be etched, e. g. a printing plate 60, is fixed against the work holder plate 16 between clamps 61 and 62 which grip the opposite edges 84 and 85, respectively, of the printing plate. The cover 12 is then lowered into position on the ledge 11 as by pulling handle 20 forward and downward.

By setting into operation motor 49, paddles 40 are revolved thereby splashing etching acid upwardly against the work on the work holder. At the same time, motor 49 drives pump 56 which withdraws etching acid from the tank and squirts it through openings 55 in pipes 53 and 54 in the etching tank. Motor 79 is also started along with motor 49, thereby oscillating the carriage plate 69 and giving the work holder plate a random oscillatory and translatory motion in a horizontal plane. The nature of this motion will be apparent on inspecting the drawing particularly Figs. 2 and 6. From these figures, it is evident that as the crank 77 is revolved the carrier plate 69 oscillates back and forth on the ways 71. As the carrier plate moves from left to right as seen in Fig. 6, for example, pinion 72 turns clockwise at a rate determined by the speed at which the carrier plate moves the pinion along the toothed portion at the left end of the rack 74 until the pinion 72 reaches the space 81 where there are no teeth on the rack. When the pinion 72 reaches the space 81, the pinion is no longer driven by the rack and instead the pinion's rate of rotation decreases since it merely coasts while it is carried along the space 81. Further movement to the right causes the gear to engage the toothed portion on the right hand end of the rack and the speed of rotation of the gear is thereby increased and again determined by the rate at which the carrier plate 69 is moved by the crank 77. When the carrier plate reaches the extreme right of its travel, the plate stops and then reverses its motion. As a consequence, pinion 72 also ceases to rotate momentarily while its translational motion changes direction, moving thereafter from right to left until the carrier plate moves to the extreme left of its travel. In moving from right to left, the motions of the pinion 72 are similar but opposite to its motions as described in proceeding from left to right. Since the carrier plate 69 is mounted on the shaft on which pinion 72 is rigidly affixed, the carrier plate undergoes the same rotational and trans-

lational motions which are random with respect to the points of impingement of the acid etching bath splashed upon the printing plate by the paddles. The randomness is achieved by virtue of the coasting feature which is built into the rack, i. e. the space 81. This space allows the rotational speed of the plate to decline quite rapidly while the pinion 72 moves from one toothed portion of the rack to the other. With this arrangement of rack teeth 73, space 81, and pinion 72, any selected portion of the surface of the work exposed to the acid bath never passes over the same spot above the bath very often during the time the work is subjected to the splash of the etching acid.

A desirable rate of rotation of the work holder plate is from about 1 to 40 R. P. M., a preferable rate being from 2 to 10 R. P. M. The translational motion, i. e. the back and forth motion of the plate may range from about 1 to 10 cycles per minute, a preferred rate being about 2 to 4 cycles per minute. Suitable rotational speeds for the paddles are from about 400 to 1200 R. P. M. It is desirable to make the length of the path of the back and forth motion of the plate holder about as long as the distance between adjacent paddle shaft centers to obtain best results.

We claim:

1. In an etching machine for etching printing plates, the combination of a tank adapted to contain a liquid etching composition; a series of paddle blades having horizontal parallel axes lying in a plane above the upper surface of the etching liquid in the tank when filled to its working level and adapted on being revolved to splash the etching liquid about the tank; upstanding baffles between the said paddle blades adapted to guide the splashed etching liquid in a generally vertical direction; a removable cover adapted to form a closure for the top of the tank so as to prevent escape of etching liquid on being splashed in the tank; a work holder plate above the baffles below the underside of the cover; motor means on the top of the cover adapted to impart to the work holder simultaneously a translatory and rotational motion in a horizontal plane.

2. An etching machine according to claim 1 having a heat exchanger in the tank below the 50 said paddle blades.

3. An etching machine according to claim 2

having perforated pipes adjacent to the heat exchanger, and a pump for circulating the liquid etching composition from the tank through the perforated pipes into the tank.

4. In an etching machine for etching printing plates, the combination of an open top tank adapted to contain a quantity of a liquid etching composition, a series of paddle blades having horizontal parallel axes lying in a plane above the upper surface of the liquid etching composition when the tank is filled to its working depth with the liquid; a vertical baffle between each adjacent paddle blade extending the length of the blade; a ledge on the inside of the tank near the rim, a cover for the tank adapted to rest upon the said ledge, said cover having a slot extending through the center an equal distance on each side of the center; a carriage plate on the top of the cover over the slot; a vertical spindle journaled on the carriage plate and extending through the said slot; a rack on the cover parallel and adjacent to one side of the said slot, said rack having teeth along a portion of each end but not in the portion intermediate the ends; a pinion mounted on the said spindle and adapted to engage the teeth of the said rack on being moved to either end of the rack; reciprocating means secured to the carriage plate for moving the same back and forth in a direction parallel to the said slot, whereby the said spindle is revolved as the pinion moves along either end of the rack; and a work holder carried by the spindle on the underside of the cover.

5. An etching machine according to claim 4 having a heat exchanger in the tank below the said paddle blades.

6. An etching machine according to claim 5 having perforated pipes in the tank adjacent to the heat exchanger, and a pump for circulating the liquid etching composition from the tank through the perforated pipes into the tank.
